Society of Soothers.

UNITED STATES PATENT OFFICE.

JOHN A. ADELL, OF ORANGE, MASSACHUSETTS, ASSIGNOR TO ADELL MANUFACTURING COMPANY, A CORPORATION OF MASSACHUSETTS.

TAPE MOISTENER.

Application filed September 21, 1922. Serial No. 589,680.

To all whom it may concern:

Be it known that I, JOHN A. ADELL, a citizen of the United States, residing at Orange, in the county of Franklin, and 5 State of Massachusetts, have invented a new and useful Tape Moistener, of which the following is a specification.

This invention relates to a device for use in moistening gummed paper or the like in 10 the form of tape for use in sealing packages and the like.

The principal objects of the invention are to provide a base or frame for a moistener in such form that it can be made of pressed metal, steel, brass or the like; to provide means whereby an extra large water pan can be provided for in such base; to provide an improved means for supporting the tank adapted to be formed of the sheet metal parts; to provide a simple and convenient roller support formed integrally with the sheet metal base; to provide an improved means for holding and insuring the permanent alignment of the standards; and in 20 general to provide a construction which will be light and inexpensive and can be manufactured in large quantities and assembled very inexpensively.

Reference is to be had to the accompanying drawings, in which—

Fig. 1 is a plan of a tape moistener constructed in accordance with this invention;

Fig. 2 is a longitudinal sectional view on the line 2—2 of Fig. 1; and

Fig. 3 is perspective view showing parts broken away.

I have shown the whole base or frame of the device as consisting of a single sheet metal stamping. This is formed up in dies 40 to provide side and end walls 10 sloping slightly. The base has a horizontal flange 11 around the bottom and an inwardly extending horizontal flange 12 around the top. The flange 11 may be provided with 45 downward projections 13 constituting feet and integral with the flange.

At one end I have provided an opening 50 between the edges of the flanges 12 below which is located a water tank 14. This tank also is of stamped metal and is held in posi-

tion by bent over lugs 15 extending in a horizontal direction from a part of the top of the frame and projecting inwardly so as to extend through perforations in the end of the tank 14. This positively holds the 55 tank up at this end and at the other end its vertical wall at the top is forced in between the end wall 10 and a flange 16 bent down from the top flange 12 and located in substantially vertical position. As the wall 10 slopes and as the tank is hung in a positive manner at the other end this end of the tank can be forced into the recess thus produced. It will not be capable of swinging down about the support at 15 without application 65 of considerable pressure. So it is kept raised off the table on which the device is supported. The tank can be held in this way largely because it does not support the finger roll 19.

In the opening above the tank 14 at the two sides I have provided two flanges 17 opposite each other and projecting down vertically into the opening below. Each of these flanges is provided with a vertical slot 75 18 having a rounded bearing at the bottom. These flanges constitute bearing supports for the finger roll 19 which has studs 20 at its ends extending into the slots 18 and supported by the rounded surfaces at the bottoms thereof.

The tank 14 extends out beyond this roll under a series of longitudinal strips 21 formed from the sheet metal of which the base is formed. Above these strips and 85 spaced at a convenient distance from them are cross bars 22 screwed on the top flange of the base to provide a space for the tape to pass under them and over the longitudinal strips. This is all the guide that is necessary. The bars 22 are secured in place by screws, bolts, or the like.

For supplying the tape to the finger roll I have provided the base with a depressed recess 25 extending across it beyond the 95 longitudinal strips 21. This recess is rectangular in shape and carries within it a bottom plate 26 which has two ears 27 projecting upwardly from it in parallel relation and perforated to support the spindle 28 of 100

the tape roll 29. The bottom plate 26 is secured in place by a screw or bolt, or more than one can be used if desired, but on account of the shape of the recess and the fact that the base 26 fills it, one is enough usually. This provides permanent alignment of the standard and insures its remaining in position.

This device is used in the same way as other tape moisteners on the market, the invention residing in the construction but it will be obvious that it is inexpensive to build and assemble; that the finger roll can be removed very readily for cleaning and the like and independently of the tank; that the tank can be drawn out at the bottom by pulling down the left hand end as shown in Fig. 2 and then detaching the right hand end for refilling and cleansing purposes; and that the tape roll is effectively secured in position and prevented from turning or getting out of alignment.

Although I have illustrated and described only a single form of the invention I am aware of the fact that modifications can be made therein by any person skilled in the art without departing from the scope of the invention as expressed in the claims. Therefore I do not wish to be limited to all the details of construction herein shown and described, but what I do claim is:—

1. In a tape moistener, the combination of a pressed metal base having an opening in its top with a tank positively supported at one end and at the top from the base so as to depend therefrom and having means at the top of the opposite end for frictionally holding that end of the tank, thus preventing its swinging downwardly about the opposite end accidentally.

2. In a tape moistener, the combination with a pressed metal base constituting the frame thereof and the support therefor, of a pressed metal water tank detachably connected at its top with the upper portion of said base and depending therefrom, integral means on the base for supporting a finger roll in the tank in position to be removed therefrom upwardly, longitudinal guide strips for the tape integral with the base extending over said tank, and means on the base for receiving a tape roll support and preventing its getting out of alignment.

3. In a tape moistener, the combination of a sheet metal base constituting the frame of the device having sloping sides and ends and provided with an internal flange at the top, said flange having an opening therethrough, means below said flange for positively supporting one end of a water tank under it, means at the other end for frictionally holding the other end of the tank and preventing the accidental swinging of the tank on its pivot downwardly, and means on the base for supporting a finger

roll down in the tank below the top of the base and independently of the tank.

4. In a tape moistener, the combination of a sheet metal base having an opening through its top, a lug projecting downwardly from one end of said opening and then longitudinally, and a flange projecting directly downwardly from the other end and spaced slightly therefrom, with a sheet metal tank having a perforation through one end wall for receiving said lug and positively supporting the tank at that end and having a vertical edge at the opposite end for projecting into the space between the end of the base and said bent over edge to frictionally hold that end of the tank and prevent its swinging on the said lug as a pivot accidentally.

5. In a tape moistener, the combination of a base having an opening in its top, with a tank positively supported at one end from the base and having means at the opposite end for frictionally holding that end of the tank and prevent its swinging about the opposite end accidentally, said base having longitudinal strips over one end of the tank for guiding the tape and being provided with two opposite ears projecting down into the tank at opposite sides thereof beyond said strips and in a vertical position adjacent to but spaced slightly from the side walls of the base, said ears having vertical slots therein extending downwardly from the top and open at the top and provided with concave surfaces at the bottom for supporting the studs of a finger roll and permitting the roll to be removed from the tank by an upward motion.

6. In a tape moistener, the combination of a base with a tank supported from the base, said base being provided with two opposite ears projecting down into the tank at opposite sides thereof in a vertical position adjacent to the side walls of the base and spaced therefrom, said ears having vertical slots therein extending downwardly from the top and open at the top and provided with concave surfaces at the bottom for supporting the studs of a finger roll and permitting the roll to be removed from the tank by an upward motion, the tank being removable by a downward motion without removing the roll.

7. In a tape moistening device, the combination with a sheet metal base constituting a frame or support for the device, of means for detachably supporting a tank within said base, means for supporting a finger roll in the tank in position to project slightly above it, and a standard consisting of a U-shaped piece of sheet metal having a flat bottom and two upwardly extending ears for supporting a roll of tape for supplying the device, said base having a depressed recess for receiving said bottom

and to which it is secured, whereby the standard is prevented by the walls of said recess from getting out of alignment.

8. In a tape moistening device, the combination with a base, of means for detachably supporting a tank within said base, and a standard having a flat bottom and two upwardly extending ears for support-

ing a roll of tape, said base having a depressed recess for receiving said bottom and to which it is secured, whereby the standard is prevented by the walls of said recess from getting out of alignment. ¹⁰

In testimony whereof I have hereunto affixed my signature.

JOHN A. ADELL.
